UNITED STATES PATENT OFFICE.

GEORGE W. VEROW, OF LINCOLN, MAINE, ASSIGNOR TO EASTERN MANUFACTURING COMPANY, OF BOSTON, MASSACHUSETTS, A CORPORATION OF MASSACHUSETTS.

WATERMARKING DANDY ROLL.

Application filed May 12, 1924. Serial No. 712,842.

To all whom it may concern:

Be it known that I, GEORGE W. VEROW, a citizen of the United States, residing at Lincoln, in the county of Penobscot and 5 State of Maine, have invented new and useful Improvements in Watermarking Dandy Rolls, of which the following is a specification.

When watermarking is effected by the 10 use of the usual dandy roll to which the desired marking element is attached, the dandy roll operating on the freshly laid pulp while it is soft and wet, it has been found that the paper machine may have to be run 15 slower than the rate determined by other conditions, in order to avoid excessive blurring of the mark.

The dandy roll is ordinarily formed reticulated as of a fine mesh wire screen rolled 20 into cylindrical form and supported by an internal frame work. The roll rests by its weight on the pulp which passes thereunder on the Fourdrinier wire and it is of very fine mesh so as to impart a pleasing surface 25 to the paper. If the dandy roll as commonly constructed and carrying watermarking elements is required to rotate rapidly to correspond with a relatively rapid passage of the paper, each watermarking element is 30 brought down against the wet pulp suddenly and forcibly causing a splashing effect, some of the water beneath the marking element being driven out forcibly laterally between the wet sheet and the tightly woven gauze 35 screen and displacing the fibers. Where the motion is relatively slow, however, this splashing effect is not in evidence, water in the pulp passing through the wire mesh adjacent to the marking element without 40 causing noticeable undesired displacement of the fibers. Again, as the marking element leaves the pulp, if the action is rapid, a suction effect is produced which acts to lift the fibers from the Fourdrinier wire, causing 45 their ends to be raised up, or even causing fibers to be removed or "picked" from the wire. The raised ends are subsequently laid by passage through other portions of the paper machine, but in a different relationship to that which they originally occupied 50 in the web. Thick and thin spots in the finished paper adjacent to the watermark as well as an imperfect mark have thus resulted.

55 I have discovered that the splash and

suction effects at relatively high speed of the roll may be very greatly reduced by employing a relatively coarse mesh wire adjacent to the marking element to allow a relatively free passage of air and water therethrough 60 adjacent the margins thereof as the device approaches and recedes from the pulp. As it is undesirable to form the roll surface as a whole of relatively coarse mesh, due to the undesirable rough, coarse surface texture 65 which would be imparted to the paper from the imprint of the roll surface thereon, it is preferable to form the main portion of the roll surface of the relatively fine mesh here- 70 fore commonly employed, utilizing the relatively coarse mesh only where the marking element is placed. As the marking element forms a cameo projection from the roll surface it acts to prevent the pulp from being brought into intimate contact with the 75 roll surface closely adjacent thereto so that the relatively coarse mesh portion does not leave its impress on the paper to a noticeable extent whereby no impairment of the 80 surface finish of the paper results therefrom.

For a more complete understanding of this invention reference may be had to the accompanying drawings in which—

Figure 1 is a perspective of a dandy roll 85 constructed according to this invention.

Figure 2 is an enlarged detail showing the marking element and its support.

Figure 3 shows the roll cut to receive the support and marking element.

Figure 4 shows a manner of forming the 90 support integral with the roll surfacing wire.

Figures 5 and 6 are detail sections on lines 95 5—5 and 6—6 of Figures 3 and 4, respectively.

The dandy roll comprises the usual roll of fine wire mesh as at 1 supported by any suitable form of frame work in cylindrical form and having spiders 2 at its ends provided with trunnions 3 by which the roll 100 may be supported for rotation about its axis in position for its periphery to rest by gravity on the freshly laid web of pulp as it passes thereunder while supported by the Fourdrinier wire. At 4 is shown a watermarking element and as illustrated herein it comprises a series of letters 5 fixed to the outer face of the wire mesh so as to project slightly beyond the periphery of the roll so as to impart a localized pressure on the pulp 110

as it comes in contact therewith as the roll rotates.

A shown in Figures 2 and 5 the marking element is fixed, as by soldering, as at 6, 5 to the outer face of a section of relatively coarse mesh wire 7, this wire mesh comprising the warp and filling strands 9 and 10 spaced apart to leave openings of substantial size therebetween. This section of 10 relatively coarse mesh is only slightly larger than the outline of the entire marking element, and as shown in Figures 3 and 5, 15 may be set within an opening in the relatively fine mesh wire 12 which comprises the remaining portion of the roll surface. This section of relatively coarse mesh to which the watermarking element is attached may be fixed to the relatively fine mesh by any suitable means, as for example, 20 by soldering.

In place of forming the relatively coarse mesh section as a separate piece from the relatively fine mesh portion of the roll, certain of the wires of the relatively fine mesh 25 material may be removed over a sufficient area to define the desired relatively coarse mesh section integral with the fine mesh portion. This is shown, for example in Figures 4 and 6, in which each alternate 30 warp and weft wire is cut adjacent to the margins of the watermarking element, the sections thus cut being removed and the exposed ends of the cut wires bent back underneath the exposed surface of the roll. 35 While as shown a section of each alternate wire is removed, two wires out of each three, or any other proportion, might be removed, if desired, this resulting in a coarser mesh. In any event, however, the 40 watermarking element is carried by the relatively coarse mesh portion which is of sufficient area to project slightly beyond the margin of the marking element. With this construction when the device is brought 45 down against the soft and wet pulp during its rotation, the air and water of the pulp may pass through the wire mesh to the inner face of the roll quite readily so that no lateral motion of the water and air from

the "splash" effect taking the pulp therewith is produced. Likewise as the element rises from the surface of the pulp the air and water may pass down readily about the margins of the marking element through the roll so that the suction effect 55 as heretofore described is relieved. It is therefore possible with this construction to run the paper machine much faster than has heretofore been possible where watermarking by the use of a dandy watermarking roll has been desired. 60

Having thus described certain embodiments of this invention it should be evident that various changes and modifications might be made therein without departing 65 from its spirit or scope as defined by the appended claims.

I claim:

1. A dandy roll having a reticulated surface, and a watermarking element fixed 70 thereto, the reticulations of said surface adjacent to said element being of larger size than those of the remainder of said surface.

2. A dandy roll having reticulated surface portions of larger and smaller mesh, and watermarking elements fixed to the portions of larger mesh. 75

3. A dandy roll having a surface portion of wire mesh, and a watermarking element 80 fixed to said surface, certain of the wires of said mesh being removed adjacent to said element to provide openings through the mesh about the margin of said element of larger size than through the remainder 85 of said mesh.

4. A device of the class described comprising a reticulated member engageable with wet pulp as sheeted on a paper machine, and a watermarking element fixed to 90 said member and arranged to be periodically impressed on the pulp, said reticulated member being of relatively coarse mesh about the margin of said element and elsewhere of relatively fine mesh. 95

In testimony whereof I have affixed my signature.

GEORGE W. VEROW.
